UNITED STATES PATENT OFFICE.

CLARENCE F. GILCHRIST AND WALTER E. RICHTER, OF TOLEDO, OHIO, ASSIGNEES, BY
MESNE ASSIGNMENTS, TO THE ELECTRIC AUTO-LITE COMPANY, OF TOLEDO, OHIO,
A CORPORATION OF OHIO.

STARTING SWITCH FOR MOTOR VEHICLES.

Application filed November 30, 1917. Serial No. 204,629.

To all whom it may concern:

Be it known that we, CLARENCE F. GILCHRIST and WALTER E. RICHTER, citizens of the United States, residing at Toledo, in the county of Lucas and State of Ohio, have invented certain new and useful Improvements in Starting Switches for Motor Vehicles, of which we declare the following to be a full, clear, and exact description.

10 This invention relates to starting switches for motor vehicles.

An object of this invention is to provide a starting pedal or switch, to be used in connection with a starting motor, which may be

15 readily actuated by the foot.

Another object is to so dispose the necessary elements of the switch, as to permit of marked ease of operation.

A further object is to provide a switch, 20 the motor parts of which may be constructed of simple metal stampings.

Still another object is to utilize, in connection with the switch, an electrical connection which will automatically maintain 25 itself in efficient condition.

Further objects, and objects relating to economies of manufacture and details of construction, will definitely appear from the detailed description to follow.

30 We accomplish the objects of our invention in one instance by the devices described in the following specification.

A structure constituting a preferred embodiment of our invention is illustrated in 35 the accompanying drawing, forming a part of this specification, in which:

Figure I is a plan view showing the starting switch.

Figure II is a sectional elevation taken 40 on the line II—II of Figure I.

Figure III is a transverse sectional view taken on the line III—III of Figs. I and II.

In the drawings, similar reference numerals refer to similar parts throughout the 45 several views, and the sectional views are taken looking in the direction of the arrows at the ends of the section lines.

As illustrated, the body casing of the switch is formed from two metal stampings, 1 and 2, the lower stamping 1 forming an oblong trough-shaped cavity 3, of

general rectangular outline as disclosed in Figure III. Laterally extending wings 4 form continuations from the recess edges 5. 55

Inserted axially within the cavity 3 is the switch proper, which consists of a resilient metal strip 6 of general arcuate outline, the end of which has a reversely curved lip 7. The other end of the strip is apertured as at 60 8 to receive the attaching bolt 9. This bolt has a head 10, and body 11, and is attached to the casing 1 by means of nuts 13, which fit over the threaded end 14. The bolt 9, has an additional function, in that it serves 65 as the binding post terminal for the electrical circuit connection 15, to which it is attached by a third nut 16. In order to give greater stiffness to the resilient strip 6, a second resilient strip 17 is interposed beneath the contact or primary strip 6, having a general curvature, when in position, the reverse of the contact strip 6, its free end having a downward curvature. 70

The lip 7 of the switch proper is designed 75 to contact with the head 18 of the bolt 19, which has a body 20 and nuts 21, similar in all respects to the bolt 9. The circuit connection 22 is held in contact with the bolt 19, by means of the nut 23, and, in order to 80 insulate the bolts 9 and 19, and the strips 6 and 17 from the casing, there is provided a U-shaped insulating strip 24 made of fibre, or any material with non-conducting properties, which is adapted to cover the sides 85 and base of the cavity 3 and to serve as washers for the bolt heads 10 and 18. Additional insulating washers 25 and 26 are also provided whereby the possibility of short circuits in the switch connections is 90 entirely removed.

The edge projections or wings 4 have apertures 27, which are adapted to register with apertures in the cover stamping 2, through which apertures the rivets 28 for 95 binding the parts together, and the screws or bolts for attaching the switch to its support, are inserted. The upper stamping 2 is the cover of the switch and is adapted to support the actuating parts. For this purpose, the central portion of the part 2 is stamped to form a circular cap or housing 29, the base of which is further stamped to form a circular apertured collar or bearing 100

30, of less diameter than the cup 29, thus forming a structure having an outer shoulder 31 and an inner shoulder 32.

The actuating means proper consists of a 5 pedal button 33, a cupped bearing 34, and an insulating plunger 35. The bearing 34 is formed by a metal stamping and is, in general, shaped as an inverted cup with the edges out-turned, forming a shoulder 36, 10 conforming with the inner shoulder 32 of the cover plate 2. The shoulder 36 is turned downward, or is parallel with the cup walls and the lower edge has a marginal flange 37, forming a bearing on the inner walls of 15 the cover plate cup 29. The sides of the cup bearing 34, extend beyond the edges of the collar 30, so that the cup is capable of sliding movement within the collar bearing. The pedal button 33 consists of a circular 20 head 38, a body 39, and a circular recessed terminal 40, adapted to fit over the cup base 41, to which it is rigidly attached by means of a rivet 42. The bottom of the button 33 is hollowed out so that it will extend over 25 the upstanding collar 30, and has an abutment 43, against which the collar will engage when the button 33 is pressed downwardly. Within the cup 34 and frictionally held thereby, is inserted the non-conducting 30 cylinder or plunger 35.

In the operation of the switch, the button 33 is pressed downwardly. The resilient strip 6, by this movement, is forced into contact with the bolt head 18, thereby completing a circuit between the two electrical terminals 15 and 22, before the button completes its downward movement. Further descent of the pedal button 33 will tend to straighten out the contact strip 6, since the 40 downward motion of the terminal 7 is arrested, and the lip terminal will therefore wipe over the bolt head 18, thereby keeping the contact area smooth and free of dust, and insuring good electrical conduction at this point. In addition, as the spring strip straightens out, the area of contact increases between the bolt head 18, and spring 6, thus reducing the resistance to the passage of current. The current resistance is further decreased by the auxiliary spring 17, which, in addition to its supporting function, serves as a second conductor for the electric current. The curved terminal of the second strip permits free sliding engagement between itself and the primary conducting strip 6.

When the pressure on the starting button is removed, the combined spring action of the strips 6 and 17 will force the connecting cylinder 35 holding cup 34 and button 33, upwardly, until the shoulder 36, of the cup contacts with the inner shoulder 32, of the casing recess 29, when further motion is prevented. In this upward movement of the 65 plunger 35, the strip terminal 7 slides in-

wardly on the bolt head 18, and by virtue of the increased curvature of the end part, there is a decrease in the area of contact, thereby increasing the electrical resistance, and reducing arcing effects at the break. 70

We are aware that the particular embodiment of our invention, here shown and described, is susceptible of considerable variation without departing from the spirit of our invention, and, therefore, we desire to 75 claim the same broadly, as well as specifically, as indicated by the appended claims.

Having thus described our invention, what we claim as new and desire to secure by Letters Patent, is:—

1. In an electric switch the combination of a casing; a plunger axially slidable through the casing; a plurality of binding post terminals in said casing and insulated therefrom; a resilient, downwardly curved, connecting strip fastened at one end to one of said terminals, and adapted, when actuated by the plunger, to contact, at its other end, with another of said binding post terminals; said strip having a reversed curvature adjacent its free end, whereby the contact area between the binding post and strip increases with the further downward movement of the plunger after a contact is established. 90

2. In an electric switch the combination of a casing; a plunger axially slidable through the casing; binding post terminals attached to the casing; a contact strip in the casing adapted to be depressed by said plunger and secured, at one end, to one of the binding post terminals and having detachable engagement at its other end, with another of said terminals; said strip being 100 downwardly curved, intermediate the two mentioned terminals and upwardly curved adjacent the second mentioned terminal, the strip making initial contact at the upwardly curved portion and, as the plunger is further depressed, making contact at the point 105 of curvature reversal.

3. In an electric switch, a plate having a cup shaped recess formed therein the bottom wall of which has an opening, a bearing member having one portion constructed to have sliding engagement with the walls of the said opening and another portion constructed to have sliding engagement with the sides of said recess, the two bearing portions being separated from one another in 115 the direction of motion and one of said members having means adapted to engage the other member to limit relative movement in one direction.

4. In an electric switch, a plate having a 125 recess formed therein, the bottom wall of which has an opening, a member having a portion adapted to have sliding engagement with said opening and having an outwardly flaring flange for engaging the side walls 130

- of said recess spaced from the said portion, and an intermediate shoulder for engaging the bottom of said recess to limit relative movement in one direction.
5. In a switch casing, a sheet metal plate having an integral cup-shaped projection formed therein, said projection having an opening in the end wall thereof, a plunger having a flared portion and having a two point bearing with said plate, one of said bearings being with said opening in the end of said projection and the other being between said flared portion and the inner surface of the side wall of said projection.
10. In a switch casing, a sheet metal plate having an integral cylindrical projection formed therein, the end wall of said projection having an aperture of less diameter than said projection, a sheet metal plunger adapted to slide in said projection and to have a plurality of spaced bearings therewith, one of said bearings being with said aperture and another being with the inner surface of the side wall of said projection.
15. In a switch casing, a sheet metal plate having an integral cylindrical projection formed therein, the end wall of said projection having an aperture of less diameter than said projection, a sheet metal plunger adapted to slide in said projection and to have a plurality of spaced bearings therewith, one of said bearings being with said aperture and another being with the inner surface of the side wall of said projection.
20. In an electric switch, the combination of a casing having a cup-shaped recess formed on one side thereof and having a flanged aperture in its base, of a diameter less than that of the recess; a cup-shaped bearing slideable in said aperture and having 30 out-turned portions designed to afford limiting stops for the sliding movement of the bearing, the extreme edge of the bearing forming a guide contact with the inner wall of the recess; a pedal button attached to the 35 base of said bearing, and having recessed edges designed to fit over the recess flange and limit the compression movement of the button; an actuating plunger held within the said bearing; binding post terminals attached to the opposite side of said casing and insulated therefrom; and resilient bridging means rigidly attached to one of said terminals and adapted when compressed by the plunger to make sliding contact with another of the terminals, thereby 40 completing an electrical circuit through the switch.
25. In an electric switch, the combination of a casing having a cup-shaped recess formed on one side thereof and having a flanged aperture in its base, of a diameter less than that of the recess; a cup-shaped bearing slideable in said aperture and having 30 out-turned portions designed to afford limiting stops for the sliding movement of the bearing, the extreme edge of the bearing forming a guide contact with the inner wall of the recess; a pedal button attached to the 35 base of said bearing, and having recessed edges designed to fit over the recess flange and limit the compression movement of the button; an actuating plunger held within the said bearing; binding post terminals attached to the opposite side of said casing and insulated therefrom; and resilient bridging means rigidly attached to one of said terminals and adapted when compressed by the plunger to make sliding contact with another of the terminals, thereby 40 completing an electrical circuit through the switch.
- In testimony whereof we affix our signatures.
- CLARENCE F. GILCHRIST.
WALTER E. RICHTER.
